UNITED STATES PATENT OFFICE.

EDWARD H. WHEELER, OF WATERBURY, CONNECTICUT.

DESIGN FOR A HEAD FOR COLLAR-BUTTONS.

SPECIFICATION forming part of Design No. 32,440, dated April 3, 1900.

Application filed February 10, 1900. Serial No. 4,831. Term of patent 7 years.

To all whom it may concern:

Be it known that I, EDWARD H. WHEELER, a citizen of the United States, and a resident of Waterbury, in the county of New Haven and State of Connecticut, have invented a certain new and original Design for Heads for Collar-Buttons, of which the following is a specification.

In the drawings, Figure 1 shows a perspective view, Fig. 2 a top plan view, and Fig. 3 a side or edge elevation, of my novel design.

As shown, the leading or material feature of my design consists in the graceful shape of a collar-button head, the same comprising a disk-like body the peripheral edge of which is thicker at the sides than at the front and rear, the latter edge being produced by a gradual bevel extending from the central portion of said head.

The head consists of a round and substantially-flat body, which is slightly thickest across its face from one edge to the other, as shown at A. Longitudinally through this thick portion is a central hole B, and the two

side edges at the entrance to the holes are of 25 a thickness equal to that of said central portion. The front and rear edges C of the head are thin, smoothly rounded, and gracefully tapered back to the central thick side edges before mentioned, it being apparent that this 30 latter taper is produced by a gradual diminution of the stock, beginning from the central enlargement and extending to the outer opposite edges, where it is finished into thin inserting-points D.

Having thus described my invention, what I claim, and desire to secure by Letters Patent, is—

The design for a head of a collar-button, as herein shown and described.

Signed at Waterbury, in the county of New Haven and State of Connecticut, this 30th day of January, A. D. 1900.

EDWARD H. WHEELER.
